ELECTRIC SWITCH

Bernard Hinks, Willenhall, England

Application December 14, 1939, Serial No. 309,284
In Great Britain December 22, 1938

7 Claims. (Cl. 175—375)

This invention relates to electro-magnetically operated switches of the type in which the movable contact carrying member is carried by the movable member of an electromagnet which may be the plunger of a solenoid or an armature, and which closes the movable contact member on the fixed contact carrying member when the magnet is energised.

An object of the present invention is to construct a switch in which the movable contact carrying member when moving from one set of contacts will automatically engage in an efficient manner, another set of contacts. A further object of the present invention is to effect an automatic change over from one set of contacts closing one circuit to another set of contacts closing another circuit after an interval of time.

In order that the invention may be clearly understood and readily carried into effect, reference may be had to the accompanying drawings on which—

Figure 1 is a front elevation of a switch constructed according to this invention, the switch being shown in the "off" position.

Figure 2 is an underside plan view of Figure 1 but showing the switch closed in the star position.

Figure 3 is a diagrammatic arrangement of the switch as shown in Figures 1 and 2, the switch being in the "off" position.

Figure 4 is a similar view of Figure 3, showing the switch closed in the "star" position.

Figure 5 is a view of a switch, as shown by Figure 3, in the "delta" position.

Figure 6 is a diagrammatic arrangement of a modified form of switch and circuit with the switch in the "off" position.

Figure 7 is the arrangement shown by Figure 6 with the switch in position with an auto-transformer in circuit and supplying a current at reduced voltage to the motor.

Figure 8 is the arrangement shown by Figure 6 showing the switch in position with the auto-transformer disconnected.

Figure 9 is a side elevation of a modified form of switch.

Figure 10 is a plan of the switch shown by Figure 9.

Figure 11 is a sectional elevation, the section being taken on line XIV—XIV of Figure 10.

Fig. 12 is a circuit diagram for the switch shown in Figs. 9, 10 and 11, the switch being shown in the "off" position.

Fig. 13 is a circuit diagram for the switch shown in Figs. 9, 10 and 11, the primary resistance being in circuit.

Fig. 14 is a circuit diagram for the switch shown in Figs. 9, 10 and 11, the resistance being cut out.

According to a convenient embodiment of this invention, as shown by Figures 1 to 5 the switch is adapted to automatically change over from the "star" to the "delta" circuit of an electric motor. The magnet comprises three limbs 11 having the windings 10 on the centre limb. The fixed contact carrying member 11a is supported by the electro-magnet and the armature 2 of the electro-magnet is supported by the links 5 which pivot on fixed spindles 4a, the spindles 4b fixed to the armature 2 being mounted in slots in the links 5. The armature 2 is thus supported by the links 5 when the switch is in the "off" position, but the armature is free to rise when in any laterally adjusted position. The fixed contact carrying member 11a carries three sets of "star" contacts 28 and "delta" contacts 31. The moving contact carrying member 1, carrying three sets of blades 29, is fixed to the armature by the connecting pieces 3. The frame 11a fixed to the electro-magnet carries the thermostatic switch 14 and the automatic change over switch 17 is also mounted on the fixed frame 11a. When the switch is in the "off" position each spindle 4b lies to one side of the pointed portion of a guide member 7, so that when the armature rises the spindle will be guided by the side 1a of the members 7 (see Figure 4). The spring 8 normally retains the movable contact carrying member in this position. When the armature is moved laterally to the right and is then lifted it will pass up between the side 1b of the guide, and the fixed frame member 12a on the left hand side of the switch (see Figure 5).

The operation of the switch is as follows: The moving switch member 1 on the armature 2, is held a distance over with the spindle 4b to one side of the guides 7, towards the "star" contacts 28, by means of the spring 8. When the start button 9 is pressed (Figure 4) the coil 10 circuit is now completed by the current passing through the leads A, B, C, D, and E to L3 to contacts 31A and this magnetises the three limbed member 11, and attracts the armature which tends to rise vertically and when the armature has moved a small distance vertically the spindles 4b will strike against the bottom curved portions of the guides 7 which will move the armature 2 and switch the moving contact carrying member 1 over towards the "star" contacts 28 and 28a until the switch blades 29 are directly under the fixed contacts 28 and 28a, the spindles 4b will now

pass on one side of the guide 7. The switch blades 29 will close on the fixed contacts 28 and 28a and so connect the motor windings in "star" Figure 2 and Figure 4 shows the switch in this position. When the switch is in this position, the button 9 is released and this springs back. The current will now pass from the lead C to F, 14, G, D, E, to L3. A secondary voltage is now induced into the secondary coil 15 which will cause a large current to pass through the lead H, 14, G, D, E, to L3, through the switch blade and the retaining blade 40, Figures 2 and 4, and the lead K. The blade 40 lies under a blade 29 and presses on the respective contact L3, when the blade 29 presses on its respective contact. When the switch has been in this position for about 10 seconds by which time the motor should have reached approximately full speed, the thermal strip 14 should have become heated by the secondary current passing through this which causes this to distort and so break the circuit of the coil 10 and when the armature tends to fall the thermal switch contacts 14 will be opened further by means of the member 16 relieving the pressure from the thermal switch and so giving a quick break of the thermal switch. When the armature is falling it will be caught by the slotted members 5, but by means of momentum of the armature 2 and the switch member 1 attached thereto when falling, such member will swing over and the member 30 will strike the automatic changeover switch 17 (Figure 5) to close the coil circuit again and the current will pass through A, B, C, F, M, contacts 11E to L3 and cause the armature to rise again, but this time it will do so by being guided by the other side of the guides 7, and the switch blades 29 will close on to the fixed contacts 31 and 31a as shown by Figure 5. The motor will now be connected in "delta." The spindles 4b are alternately guided between a guide 7 and a frame member 12a. The spring 8 assists in the changeover movement. The thermal switch 14 is only in series with one of the retaining contacts 13 and the said secondary thermal switch circuit is completed when the contactor is in the "star" position. There are two retaining contacts 13 which are respectively for the "star" and the "delta" positions. The thermal switch 14 acts as the retaining switch when the switch is in the star position, current passing from L2, A, 10, B, contacts 9a, C, F, 14, 9, D, E to L3. The auto-changeover switch 17 acts as the retaining switch when the switch is in the "delta" position, current passing from L2, A, 10, B, contacts 9a, C, F, M, 17, E to L3. The secondary coil 15 is switched "off" when the contactor is in the "delta" position.

In lieu of utilizing a "star" and "delta" arrangement of circuits an auto-transformer is utilized for supplying current at reduced voltage when starting up a motor. A convenient embodiment of such an arrangement is shown by Figures 6, 7 and 8. The switch is substantially the same as that shown by Figures 3 to 5 except that it is adapted to cut out or include an auto-transformer of known type in the circuit in accordance with the position of the switch when in the "on" position. In this construction each pair of switch blades comprises a long blade 29a and a short blade 29b. When the switch is in the position shown by Figure 10 the short blade and the long blade bridge the contacts, respectively, 32 and 33 and include the auto-transformer 34 into the circuit. When the switch is in the posi-

tion shown by Figure 11, the long blade 29a bridges the contacts 35 and cuts out the auto-transformer and allows the current at full voltage to pass to the motor. The circuits except 5 for the cutting out or putting in the auto-transformer instead of having the "star" and "delta" circuits, are as described with reference to Figures 3 to 5. In all the drawings the main leads are indicated by L1, L2 and L3 and the motor leads by M1, M2 and M3. The auto-transformer 10 is of the known type.

In lieu of the armature of the electro-magnet being mounted to move laterally with the movable switch such armature may comprise the plunger of a solenoid, the movable switch member being mounted to move laterally thereon such an arrangement is shown by Figures 9, 10 and 11. The plunger 40 of the solenoid coil 41 carries the guide bar 42 which slides on the fixed bolts 43, the bolts being fixed to the frame members 44 fastened to the switch casing. The frame 45 is fixed to the bolts 43. The movable switch member 46 carrying the contact blades or bridge contacts 47 is attached to the plunger 40 by 25 means of the links 48 so that the switch member 46 can bodily swing laterally in relation to the solenoid. The switch member 46 is normally held in one position by the weight bar 49 which rests on the bar 42 and in this position the 30 switch member 46 is in position, when the solenoid is energised for the bridge contacts to engage the fixed contacts 50 of the fixed contact member on the frame 45 to include the primary resistances 51 into the circuit. The automatic 35 action of the switch is similar to that described with reference to Figures 6, 7 and 8. The thermostatic switch bar 51a is closed on the contact 52 by the projection 53 and after an interval of time, the thermostatic switch breaks and 40 energises the solenoid. The plunger with the switch member 46 is opened by the springs 54 and when the switch member 46 reaches the limit of its outward movement the momentum of the weight bar 49 causes the switch member 45 to swing over and close the spring blade switch contact 55 against the contact 56 and energise the solenoid. This causes the plunger to be attracted to move the switch member into the "on" 50 position with the bridge contacts 47 engaging the fixed contacts 50. The fixed contacts 50 are separated by the insulating walls 58. 59 are the retaining switch contacts which coact with the spring arm contact 60 on the switch member 46. The switch arm 55 is located in a slot in the member 61 carried by the switch member 46, to prevent movement of the arm 55 when in the 55 position shown by Figure 14. The spring blade contact 55 is fixed at one end to the fixed contact carrying member and near its other end it passes through the slot in the member 61. The spring blade contact therefore moves laterally with the movable contact carrying member 46 and the said slot permits the member 61 to slide in relation to the contact 55. The switch contacts 55, 56, 60 remain pressed together whilst the main switch is closed. The contact 56 is at its inner end connected to the fixed contact carrying member. The switch is guided into the correct position by the guide members 62 and 63 which coact respectively with the projection 64 and a bridge contact blade 47. In the position shown by Figure 9, the blade 47 will coact with the inclined upper edges of the guide members 62, 63 to correctly position the movable contact member, if necessary, when attracted to the fixed contact carry-

ing member. When the movable contact carrying member is swung over, the projection 64 will then be in a similar position to co-act with the said inclined upper edges of the guide members 62, 63 if necessary. The circuit diagrams of Figures 12, 13 and 14 are exactly the same as that shown by Figures 3 to 5 except that the contacts 50 connected respectively to the leads from the mains L₁, L₂, L₃ and the leads to the motor M₁, M₂, M₃, are substituted for the contacts 28a, 31a, from the mains and the contacts 28 and 31 to the motor, to adjust the switch from a star-delta arrangement to an arrangement in which a primary resistance is put in or cut out.

I claim:

1. An electro-magnetically operated switch comprising an electro-magnetic device, a movable contact carrying switch member attached to the movable member of the electro-magnetic device and supported on pivoted links so that when in the "off" position it is capable of swinging laterally, a row of bridge contacts carried by said movable switch members a fixed contact carrying member having contacts which can be selectively bridged to complete either of two electric circuits the movable switch being normally positioned so that when attracted by the electro-magnetic device it will bridge the contacts of one circuit, a thermostatic switch for breaking the circuit of the electro-magnet to cause the movable contact member to move into the "off" position, means for causing the movable contact member to swing over when in the "off" position into position for completing a second circuit, and a switch operated by the said swinging over of the movable contact member for energising the electro-magnet and moving the switch member into position for closing the said second circuit.

2. An electric switch as claimed in claim 1, in which the automatic means for swinging over the movable contact member when in the "off" position comprises a weight pivoted to the said pivoted links.

3. An electric switch as claimed in claim 1, in which the current for passing through the thermostatic switch is induced by the main coil of the electro-magnet.

4. An electric switch as claimed in claim 1, in which the thermostatic switch is closed by a projection on the movable switch contact carrying member when moved into the "closed" position.

5. An electromagnetically operated selecting switch, comprising an electro-magnetic device, a movable contact carrying switch member attached to the movable member of the electro-

magnetic device, a plurality of parallel bridge contacts carried by the said movable switch member, a fixed contact carrying member, and means for mounting the said movable switch member so that it automatically moves in a lateral direction when moving from one contacting position to place such member into position for being attracted to contact a second set of contacts and a switch which is operated by the lateral movement of the movable contact carrying member for energising the electro-magnet to cause the movable contact carrying member to move to contact such second set of contacts.

6. An electro-magnetically operated selecting switch comprising an electro-magnetic device, a movable contact carrying switch member attached to the movable member of the electro-magnetic device and supported on pivoted links so that when in the "off" position it is capable of swinging laterally, a row of bridge contacts carried by said movable switch member, a fixed contact carrying member having contacts which can be selectively bridged to complete either of two electric circuits, means for automatically swinging the movable contact carrying member laterally into position, for being raised into engagement with the second set of fixed contacts, when moving from one contacting position and a switch, which is operated by contact with the movable contact carrying member when such member swings laterally, for energising the electro-magnet to cause the movable contact carrying member to engage the said second set of contacts.

7. An electro-magnetically operated selecting switch, comprising an electro-magnetic device, a movable contact carrying switch member attached to the movable member of the electro-magnetic device, a plurality of parallel bridge contacts carried by the said movable switch member, a fixed contact carrying member, and means for mounting the said movable switch member so that it automatically moves in a lateral direction when moving from one contacting position to place such member into position for being attracted to contact a second set of contacts, a switch which is operated by the lateral movement of the movable contact carrying member for energizing the electro-magnet to cause the movable contact carrying member to move to contact such second set of contacts and means for de-energizing the said electro-magnet after an interval of time so that the movable switch member will be free to move from one contacting position to the other.

BERNARD HINKS.
